DISPLAY BOX OR SIMILAR ARTICLE

Jerome Gould, Encino, Calif., assignor to Design Properties, Inc., Los Angeles, Calif., a corporation of California

Filed May 10, 1965, Ser. No. 85,207

Term of patent 14 years

(Cl. D58—11)

FIGURE 1 is a side perspective view of a display box or similar article showing my new design;

I claim:

The ornamental design for a display box or similar article, as shown and described.
